UNITED STATES PATENT OFFICE

90,779

DESIGN FOR A SIGNALING DEVICE

Margaret J. Metzger, Houston, Tex.

Application July 31, 1933. Serial No. 48,883

Term of patent 14 years

To all whom it may concern:

Be it known that I, MARGARET J. METZGER, a citizen of the United States, residing at Houston, in the county of Harris and State of Texas, have invented a new, original, and ornamental Design, for a Signaling Device of which the following is a specification, reference being had to the accompanying drawing, forming part thereof.

The figure is a perspective view of a signaling device, showing my new design the rear side of the design being plain.

I claim:

The ornamental design for a signaling device as shown and described.

MARGARET J. METZGER.
